UNITED STATES PATENT OFFICE

97,816

DESIGN FOR AN AUTOMOBILE SEAT SLIP

Roman Jaramillo, El Rito, N. Mex.

Application May 16, 1935, Serial No. 56,875

Term of patent 7 years

To all whom it may concern:

Be it known that I, Roman Jaramillo, a citizen of the United States, residing at El Rito, in the county of Rio Arriba and State of New Mexico, have invented a new, original and ornamental Design for an Automobile Seat Slip, of which the following is a specification, reference being had to the accompanying drawing, forming part thereof.

Figure 1 is a plan view of an automobile seat slip, showing my new design.

Figure 2 is a fragmentary plan view of the end portion of the decorative stripe shown in Figure 1, drawn to an enlarged scale and bringing out the details of the design feature.

I claim:—

The ornamental design for an automobile seat slip, as shown and described.

ROMAN JARAMILLO.
